UNITED STATES PATENT OFFICE.

WILLIAM F. KIESEL, JR., OF ALTOONA, PENNSYLVANIA.

CAR-COUPLING.

SPECIFICATION forming part of Letters Patent No. 793,592, dated June 27, 1905.

Application filed November 5, 1904. Serial No. 231,510.

To all whom it may concern:

Be it known that I, WILLIAM F. KIESEL, Jr., a citizen of the United States, residing at Altoona, in the county of Blair and State of Pennsylvania, have invented certain new and useful Improvements in Car-Couplers, of which the following is a specification.

My invention relates to improvements in the centralizing devices whereby the draw-bar and coupler-head are returned to their normal central positions after having been swung to one side or the other when passing around curves or when cars are coupled together when not in true alinement; and the object of my improvements is to provide means whereby both the draw-bar and the coupler-head will be centralized by a single spring and at the same time to provide for a greater extent of lateral motion than that which is possible with the devices now in use.

A further object is to so arrange the coupler-head and centralizing devices with reference to the draw-bar that the draw-bar alone may move laterally or the coupler-head alone may move laterally, or both the coupler-head and draw-bar may have lateral movement, and when released both the coupler-head and draw-bar will be brought back to their normal central positions by the one centralizing-spring. I attain my objects by means of the arrangement and construction of the draw-bar and coupler-head connections and centralizing devices as illustrated in the accompanying drawings, in which—

Figure 1 represents a side elevation of a coupler-head and draw-bar with my improved centralizing device applied thereto; Fig. 2, a plan view of the same with a portion of the draw-bar broken away; Fig. 3, a similar view with the draw-bar and coupler-head thrown over to one side; Fig. 4, a transverse vertical section on the line xx in Fig. 2 looking to the right, the spring-actuated followers being shown unbroken and with the centralizing spring removed; Fig. 5, a vertical transverse section on the line xx in Fig. 2 looking to the left; Fig. 6, a modified form of my centralizing device with the parts shown in vertical longitudinal section; Figs. 7 and 8, plan views of the same with the parts broken away.

to show the relative arrangement and mode of operation, and Fig. 9 a transverse vertical section on the line yy in Fig. 7 with the centralizing-spring removed.

Like numerals designate like parts in the several views.

In Fig. 1 the numeral 1 designates the end sill of a passenger-car platform or vestibule, beneath which is a shorter end sill 2, against which the ends of the draft-sills 3 3 abut. Attached to the draft-sills is a stirrup-plate 4, which supports the outer end of the draw-bar 5, said draw-bar being pivoted at its inner end at 6 to the draft-yoke 7, which in Figs. 1 and 2 is shown as applied to an ordinary type of draft-gear. The draw-bar 5 is bifurcated, and to its free end the coupler-head 8 is pivoted by means of the pivot-pin 9. Between the arms of the draw-bar and pivoted to the pivot-pin 9 are two spring-actuated followers 10 10, 70 the extremities 11 of which bear against the plates 13, which are secured inside the draft-sills above the stirrup 4. The centralizing-spring 12 is held between seats formed on the extremities 11 and acts to throw the followers 75 against the bearing-plates 13, said plates also acting as stops to limit the expansion of the followers. The followers are constructed with inwardly-projecting webs which pass across the center line of the draw-bar and are provided 80 with lips 14, turned in opposite directions and engaged by stops 16, which project inwardly from the upper and lower arms of the draw-bar, as shown more clearly in Fig. 4. The coupler-head 8 is chambered to receive the 85 ends of the draw-bar and the followers, said followers acting upon side bearings 15, formed at the opening of the chamber by the vertical sides thereof to hold the coupler-head in its central position. The draw-bar is held in its 90 central position by means of the lips 14 on the followers, which exert pulls in opposite directions on the stops 16, as will be readily understood from an inspection of the drawings. The followers are so constructed that 95 when their ends are pressed together to compress the spring their web portions will pass over and under each other. In Fig. 3 the draw-bar is shown thrown over to its extreme left-hand position. For this movement of the 100

bar the stop 16 on the upper arm will have acted upon the lip 14 to force the right-hand follower toward the left-hand follower to compress the spring. The left-hand follower 5 slides and turns on the plate 13 by reason of the side motion of the pivot-pin 9, thereby maintaining the spring-seats on the two followers in alinement with the center line of the spring and also acting to further compress 10 the spring. When the coupler-head is relieved of its side thrust, the spring will act to throw the followers apart, thereby causing the lip 14 on the upper or right-hand follower to act on the stop 16 on the upper arm of the 15 draw-bar to force the draw-bar back to its central position. In the full-line position the coupler-head is shown in its central or normal alinement with the draw-bar; but it will be evident that the coupler-head may have an 20 additional movement to the left or into the extreme position indicated by the broken lines. This independent movement of the coupler-head is permitted by reason of the drawing together of the followers, which leaves a clearance 25 between them and the side bearings 15. If the side thrust on the coupler-head is from left to right, the draw-bar will be swung over to the opposite side from that shown in Fig. 3 and the stop 16 on the lower arm of the 30 draw-bar will act on the lip 14 of the left-hand follower to throw said follower over to the right, and so compress the spring, and an additional side motion of the coupler-head to the right will be permissible to the same extent 35 as in the left-hand position. (Shown in Fig. 3.) A lateral motion in the coupler-head independent of the draw-bar is also permissible while the draw-bar remains in its central position, since when the coupler-head is swung 40 to either the left or right around the pivot-pin the side bearings 15 will act on one or the other of the followers to compress the spring, the spreading apart of the followers acting upon the side bearings to return the coupler-head 45 to its central position when the side thrust is released. This side motion of the coupler-head independent of the draw-bar is of special benefit when coupler-heads are brought together in coupling cars, as it provides 50 a certain facility of side motion which relieves the strain on the coupler-heads that would otherwise take place when the coupler-heads to be united are not in true alinement. In the modification shown in Figs. 6 to 9, 55 inclusive, I have shown a shorter draw-bar and a different construction of the centralizing-followers. In this modification the draw-bar is pivoted upon the spring-followers 18 of the draft-gear, the rear follower being shown 60 in Fig. 8 as acting as the pivot for the draw-bar. The bifurcated arms of the draw-bar in this modification pass into depressions formed on the upper and lower sides of the coupler-head and are united thereto, as before, by a 65 pivot-pin 9. The coupler-head is formed with

laterally-projecting curved arms 19, positioned between the arms of the draw-bar and in engagement with the plates 13, which are attached inside the draft-sills above the stirrup-plate 4, as before. The outer surfaces of the 70 arms 19 are curved, so as to ride upon the side plates 13 when the coupler-head is turned in one direction or the other. These arms on the inside are channeled, so as to support and guide the followers 20. These followers carry 75 at their extremities the centralizing-spring 12 in the same manner as before described. Instead of the stops 16 on the draw-bar a pin 22 passes through from arm to arm, the followers being provided with curved slots at 21, 80 through which the pin also passes. At their forward ends the followers are provided with lugs 23, which ride along curved surfaces 24, formed at the upper and under side of the coupler-head between the arms 19. In this 85 modification lateral motion in the coupler-head takes place coincident with lateral motion in the draw-bar, so that when the coupler-head swings to the one side or the other on the pivot-pin 9 a corresponding lateral motion will be imparted to the draw-bar, as will be understood more clearly from an examination of Fig. 8. When the draw-bar is thrown over to one side, the pin 22 will act upon one 90 of the followers to draw it toward the other, the lug 23 on such follower sliding along the concave surface 24, thereby permitting a slight turning of the follower about the pin, upon which it fulcrums, and bringing its spring-seat into alinement or approximate 95 alinement with the spring-seat on the other follower, which latter follower is moved inward at the same time by the turning movement of the coupler-head. The effort of the spring to force the followers apart causes the 100 follower which has been thrown away from the arm 19 of the coupler-head to slide back into normal position when the side thrust on the coupler-head is released, thereby drawing the draw-bar and coupler-head back to their 105 central positions.

Of the two forms herein shown and described the first is probably more serviceable for passenger-cars, where there is a long reach from the draft-springs to platform end sill, 110 while the second is preferable for freight-cars. In the first form there is more freedom of motion in the coupler-head, and, moreover, it is free to move independently of the draw-bar, while in the second form there must be coincident movement in both coupler-head and draw-bar. In both of these forms the one centralizing-spring acts on both the draw-bar and coupler-head to return them to their central normal positions when released from side 115 thrust, and any construction of the parts of the centralizing device which will accomplish this result with the use of but one spring will come within the scope of my invention.

Having thus described my improved cen- 120

tralizing device and without confining myself to the specific details of construction shown and described herein, what I claim as my invention, and desire to secure by Letters Patent, is—

1. A car-coupler comprising a draw-bar mounted to swing laterally, a coupler-head pivoted on the draw-bar, followers mounted on the draw-bar and projecting from each side thereof, a spring between said followers, side bearings to receive the thrust on said followers, and means whereby the followers will be made to approach one another when the coupler-head is thrown out from its central position.

2. A coupler-head comprising a draw-bar mounted to swing laterally, a coupler-head pivoted on the draw-bar, a guideway for the draw-bar, followers mounted on the draw-bar and projecting from each side thereof, and a spring between said followers acting in conjunction with side bearings in the guideway to centralize both the draw-bar and the coupler-head.

3. A car-coupler comprising a draw-bar mounted to swing laterally, a coupler-head pivoted on the end of the draw-bar, a guideway for the draw-bar, a pair of oppositely-disposed followers mounted on the draw-bar and lying between side bearings in the guideway, a spring between said followers acting to spread them apart, and means whereby the draw-bar will move one or the other of said followers to compress the spring when swung to one side or the other.

4. A car-coupler comprising a draw-bar mounted to swing laterally, a coupler-head pivoted on the end of the draw-bar, a pair of followers pivoted on the coupler-head pivot-

pin, a spring between the free ends of the followers, and stops on the draw-bar and side bearings on the coupler-head engaging the followers, whereby one or the other of the followers is actuated to compress the spring by lateral motion in either the draw-bar or the coupler-head, or both. 40

5. A car-coupler comprising a bifurcated draw-bar mounted to swing laterally, a coupler-head pivoted on the bifurcated ends of the draw-bar, a pair of followers mounted between the arms of the draw-bar, side bearings to limit the spread of the followers, a coiled spring acting to force the followers apart, and connections between the followers and the draw-bar and coupler-head whereby the lateral displacement thereof will act through the followers to compress the spring. 50

6. A car-coupler comprising a bifurcated draw-bar mounted to swing laterally, a coupler-head having a chamber to receive the bifurcated ends of the draw-bar, a pivot-pin by which the coupler-head is coupled to the draw-bar, a pair of followers mounted between the arms of the draw-bar and also pivoted on said pivot-pin, side bearings to limit the spread of the followers, a coiled spring acting to force the followers apart, and stops on the draw-bar and side bearings on the coupler-head engaging the followers, whereby one or the other of the followers is actuated to compress the spring by lateral motion in either the draw-bar or the coupler-head, or both. 60

In testimony whereof I have affixed my signature in presence of two witnesses.
